C. H. SANDERSON

INCLOSURE FOR SPLICED ENDS OF ELECTRIC CABLES

Filed May 21, 1921

By his Attorney

H. Carlson

UNITED STATES PATENT OFFICE.

CLARENCE HERBERT SANDERSON, OF NUTLEY, NEW JERSEY, ASSIGNOR OF ONE-HALF
TO JOHN P. STETSON, OF NEW YORK, N. Y.

INCLOSURE FOR SPLICED ENDS OF ELECTRIC CABLES.

Application filed May 21, 1921. Serial No. 471,415.

To all whom it may concern:

Be it known that I, CLARENCE HERBERT SANDERSON, a resident of Nutley, in the county of Essex and State of New Jersey, have invented certain new and useful Improvements in Inclosures for Spliced Ends of Electric Cables, of which the following is a specification.

This invention relates in general to joints 10 for lead pipes used in enveloping electric conductors and it especially appertains to clamp couplings for such conduits.

The main object of the invention is to provide an improved solderless joint or coupling between the jacket that surrounds 15 spliced ends or portions of an electric cable and the sheaths covering the latter.

Another object is to produce a coupling of the character described adapted to join 20 pliant tubular elements of different sizes, one coupling member serving to expand the end of the smaller element, while another member compresses the extremity of the larger element.

25 A further object is the production of a coupling of the nature set forth having co-operating clamping members associated with the tubular elements joined thereby intermediately as well as externally and internally of the same.

Still another object is the provision in 30 a coupling of the type specified of means for tightly clamping the ends of differently sized tubular elements, independently of one another, and without the use of interposed packing.

A still further object in producing a coupling of the class mentioned is so to arrange the members which exert the clamping 40 pressure upon the ends of the tubular elements, that they shall be separate from the means for effecting such pressure.

An additional object is to furnish a coupling of the species referred to, including 45 non-rotating clamping members actuated by rotatable means.

A supplementary object is to supply a coupling of the genus alluded to wherein the means for exerting pressure upon the 50 clamping members also serve to dissipate electrostatic charges occurring between such members and the cable insulation in order to save the latter from injury.

A general object is to afford an improved 55 coupling for the purpose expressed, com-

posed of few, simple and durable parts, amenable to economical manufacture, readily assembled or taken apart, and which will effectively preclude water or moisture from reaching the cable splice.

Other objects and advantages of the invention will become apparent as the specification proceeds.

With the aforesaid objects in view, the invention consists of the novel combinations and arrangements of parts hereinafter described in their preferred embodiments, pointed out in the subjoined claims, and illustrated on the annexed drawing, wherein like parts are designated by the same reference characters throughout the several views.

In the said drawing:-

Figure I is a fragmentary side elevation, partly in section, showing a cable splice in- 75 closure embodying the present invention;

Fig. II is a fragmentary sectional elevation illustrating a modified structure of the inclosure;

Fig. III is a partial end view looking 80 from the left side of Fig. II; and

Fig. IV is a similar view taken from the right-hand side of the same figure.

The advantages of the invention as here outlined are best realized when all of its features and instrumentalities are combined in the one and same structure, but, useful devices may be produced embodying less than the whole.

It will be obvious to those skilled in the 90 art to which the invention appertains, upon becoming conversant with the details thereof, that the same may be incorporated in several different constructions. The accompanying drawing, therefore, is submitted 95 merely as showing the preferred exemplification of the invention.

Referring now to the aforesaid views for a detailed description of the invention, the known parts of the cable splice and housing 100 therefore have been designated by reference letters, of which A and B denote electric cables or conductors respectively covered with insulation, as C and D, sheathed in turn by thin pliant tubular elements or lead 105 pipes E and F. The wires constituting the cables A and B are joined by a splice G in the customary manner, for example, by uniting the corresponding wires of the cable ends. 110

H designates another pliant tubular element which may be a lead jacket of larger diameter than the conduits E, F, and is adapted to bridge the space between the adjacent terminals of the latter for the purpose of surrounding and concealing the splice G, while remaining out of contact on all sides thereof.

The said jacket H is preferably formed in its top side with a pair of bosses K struck up from the wall thereof and spaced apart as shown in Fig. I. Pipe plugs J are screwed into threaded openings provided therefor, in these bosses. After the splice is completed and the jacket has been secured in position, the plugs J may be removed to permit of pouring an insulating compound into the interior of the former. This compound is supplied thru the opening in one of the bosses, while the air is allowed to escape during the filling operation by way of the other opening.

A jack constructed as described, has in prior practice been secured to the lead sheaths E and F, by wiping soldered joints at the opposite ends thereof. But in carrying out the present invention, such expedients are discarded and the jacket is detachably retained in position to provide impervious coupling means by the device next to be referred to.

In securing the jacket to the cable sheaths, either end of the former is held to the respective sheath in the same manner, and accordingly for the sake of brevity, the detailed description of the method followed in keeping one end of the jacket element in position to the adjacent sheath element, will apply equally as well to both ends of these elements.

When one end of the lead pipe E is to be attached to the proximate extremity of the said jacket element H, an intermediate coupling member or sleeve 5 is employed, which as represented in Fig. I of the drawing, is substantially bowl-shaped in cross section. One part 6 of this sleeve is contracted to closely fit over the outside of the said element E near the adjoining terminal thereof, while another portion 7 of the said sleeve member which is enlarged, is adapted to enter inside the adjacent end of the jacket H.

The interior of the sleeve 5 between the part 6 and the portion 7, is internally bellied or flared as at 9, from the contracted towards the enlarged end thereof. The said flaring intermediate portion 9 leads into the base of an internal beading 10 which serves as a retaining ledge, the purpose whereof will be more fully hereinafter referred to. Directly adjacent to the bead 10, the said enlarged portion of the sleeve member is provided with a smooth cylindrical bore 12, beyond which the former

is internally threaded as at 13, for the remainder of the distance to the inner extremity thereof.

The lead sheath E, which is removed a few inches back from the insulation C beyond the splice G, is subsequently expanded thru the employment of a suitable implement so as to fill up and partake of the interior configuration of the convex bell-mouth 9 and the thereto appertaining beading 10.

An annular compression member or follower 15 of appropriate internal diameter to be slipped over the outside of the insulation envelop C, is entered into the bore 12 of the coupling sleeve. This compression member is adapted to cooperate with the belled surface 9 and interior bead 10 of the sleeve 5, and accordingly the juxtaposed faces of the said follower is of corresponding configuration. That is to say, the external surface of the follower 15 is formed with a circumferential flute 17 supplementary to the beading 10, and has a similar sweep 18 complementary to the convex flare 9. In a like manner, the outer periphery of this follower is given the shape of a cylindrical rim 19 correlated to the bore 12, and adapted to cooperate therewith in order to guide the follower 15, prevent its jamming and consequent digging of the latter's relatively sharp inner edge 20 into the envelop C of the cable. By the construction above set forth, the sleeve and its follower are capable collectively of firmly gripping the expanded end of the conduit E and clamp the same rigidly to the first mentioned member. Due to the squeezing of the edge of the lead sheath E between the beading 10 and the flute 17 of the follower, not only increases the tightness of the joint, but also makes it impossible for the sheath to become detached from the sleeve member.

The means for actuating or applying pressure upon the inner end of the follower 15 is represented as consisting of a shell-like bushing 21 which has an externally threaded portion 22 arranged for screwing into the interior threads 13 of the sleeve member 5. The inner extremity of the bushing 21 which tapers in a direction away from the threaded portion 22 thereof, as at 23, may be conveniently formed cylindrical on the outside, and provided with an inner flared polygonal face, indicated at 24. The purpose of the latter is to increase the internal surface of the tapered part 23 and thereby more readily carry off such electro-static currents as may leak thru the insulating covering of the cable. In order that the shell 21 which in reality constitutes a nut, may be screwed tightly into the threaded portion of the sleeve 5 to force the follower to a seat, the after end of the said shell-like nut is provided with notches 25 for the reception of a suitable spanner or wrench. During the

tightening operation sufficient pressure may be exerted upon the follower to press the leaden conduit into immediate contact with the cooperating parts and effect a joint which will be impervious to moisture.

An important feature of this invention resides in the fact that when securing the coupling members and the conduit one relatively to the other, all parts which directly engage 10 the latter are free from rotative movement, the only rotating part being the nut 21. In practice, the external surface of the reduced part 6 of the coupling sleeve 5 may be formed polygonal, as shown at 26, so that 15 the same may be gripped with a wrench at this point to preclude it from turning while the shell nut 21 is being screwed up to force the follower 15 into the spread end of the sheath or conduit E. Thus it will be seen 20 that the non-rotatable parts are simply forced together to clamp the walls of the conduit therebetween. Consequently there is no liability to disrupt the clamping surfaces of the pliant sheath, the same as is 25 the case when a hard metallic part is rotated against a soft metal such as lead, which is apt to become torn or cut, rendering it impossible to secure a tight seal or joint. However, in the present invention 30 these difficulties are overcome since there are no rotatable parts to engage with the conduit sheath.

The outside of the after end of the part 7 of the coupling member 5 has a cylindrical 35 contour 27 of a diameter to fit the inside of the jacket H. The said cylindrical part 27 extends for a short distance from the inner end of the sleeve member 5 and is conjoined by a convexly curved surface 28 which terminates at the base of a circumambient bead 29, for a purpose corresponding to the beforenamed beading 10. In direct proximity to the said bead 29, the sleeve 5 is formed with a smooth cylindrical portion 30 intermediate of which and the before mentioned 40 polygonal outer end 26, the said sleeve is exteriorly provided with screw threads 32.

With the said threaded portion 32 is adapted to engage internal screw threads 50 33 provided in an annular clamping nut 34. The latter acts against a follower or compression member 35, the interior of which is supplementary to the external portion of the coupling sleeve 5 embraced thereby. 55 That is, the follower is furnished with a concave recess 36 of similar contour to the convex surface 28, and adjoining the former is an annular flute 37 shaped to correspond with the beading 29, being further provided 60 with a bore 38 complementary to the cylindrical surface 30.

In order to enable the follower 35 to properly operate upon the adjacent end of the jacket H, the latter is beat inwardly so as to substantially conform to the shape of

the convex surface 28 and adjoining bead 29. The said follower is thereupon slid with its bore 38 riding on the cylindrical portion 30 of the sleeve member 5, until the concaved recess 36 in the follower takes over 70 the end of the jacket thus formed. The clamping nut 34 is then screwed upon the threads 32 and may be tightened by means of a wrench applied to the polygonal sides of the former, being brought to forcibly 75 bear upon the follower which thereby tightly compresses and grips the end of the said jacket H.

The structural elements of the present invention have been set forth in detail hereinabove, and the manner in which the same is applied in practice will now be described.

On each terminal of the cables, a set of members 5, 34 and 35 is slipped along the former back a certain amount so as to locate 80 them out of the way of subsequent operations. The jacket H is also placed over one cable end and slid upon the latter for any appropriate distance. The lead sheaths or conduits E and F are next cut back a few 85 inches from the ends of the respective cables to expose the insulating envelopes C and D, whereupon the extremities of the lead conduits are expanded to substantially correspond to the internal flare of the coupling 90 sleeves 5 in the manner hereinbefore recited. After this has been done, the coupling sleeves are drawn toward one another so as to engage the outside of the conduits' flared portions. The followers 15 are then entered 95 into the larger ends 7 of the sleeve members 5 and lodged against the inside of the flared faces of the conduits. The clamp-bushings 21 are next screwed up against the followers to cause the latter to tightly grip the conduits within their respective coupling members as before described.

This having been accomplished, the insulations C and D are cut away adjacent the terminals of the cables which are thereupon brought into alignment, so that the corresponding strands or wires thereof may be spliced together. After the splice has been completed, the same is wound with adhesive tape or other suitable insulating material.

The lead jacket H is now moved longitudinally of the cable from the place which it has up to this time occupied, into a position wherein it will bridge the splice G, with its opposite ends embracing the coupling members pertaining to the respective cables. The jacket is then cut to appropriate length and its opposite extremities made to conform to the curvatures of the surfaces 28 and 29 on the exteriors of both of the coupling members 5.

The external followers are next moved toward one another into a position to encompass the opposite end portions of the jacket H whereupon the clamping nuts 34 are 130

4
screwed up sufficiently tight against the followers 35 so as to effect a tight joint between the parts in the same manner as was produced with reference to the internal followers 15. At the conclusion of these operations, the jacket will have been securely as well as detachably mounted in position to surround and conceal the splice and provide a covering or housing therefor which will be 14 impervious to moisture.

The screw plugs J are now removed and a suitable insulating medium, in fused state, is poured thru the opening in one of the bosses K, while the displaced air within the 15 jacket is allowed to find exit by way of the hole in the other boss. After the jacket has been flooded or filled, the plugs J are returned to position and the assembly is complete.

20 It will be apparent from the foregoing description, that the present invention may be economically applied to a cable splice even when working in close quarters, such for example, as in manholes, trenches, openings in walls and the like. For underground work where weight does not have to be taken into consideration, the different clamping members entering into the construction, may be made of cast iron galvanized and then provided after assembling with a coating of asphaltum applied exteriorly thereover. In aerial construction, the parts are preferably formed of aluminum or of a die-cast alloy of the latter.

25 An important feature of this invention, resides in the fact that the same may be employed without necessitating the use of fires or blow torches for the melting of lead required in the wiping of joints as heretofore.

30 This is of particular value when operating in walls of buildings or in manholes. In the former case, the torch is apt to set the building afire, while in the latter instance, fires in manholes and even carrying of hot 45 ladles with molten lead, not infrequently cause the ignition of inflammable gases which accumulate in the manhole due to leaky gas mains or for other reasons well known to those skilled in the art. In applying the 50 construction under consideration, no heat whatsoever is needed and consequently the danger of fire is eliminated.

In Figs. II, III, and IV a modified construction of a clamp joint embodying the 55 invention is illustrated. In these views a coupling member 5^a is formed with serrated convexly curved internal and exterior sheath and jacket engaging surfaces 9^a and 28^a respectively. In this structure, clamping members 15^a and 35^a which coat interiorly and externally with the said coupling member 5^a, correspond to the similar followers 15 and 35 in Fig. I. But, instead of being seated by a clamping bushing or like nut, they are forced against the ex-

panded or contracted extremities of the sheath E¹ or jacket H¹, by screw bolts 22^a and 32^a respectively. The latter are threaded into tapped holes 41 extending in an axially parallel direction longitudinally thru 70 the coupling member 5^a.

The heads of the screws 22^a bear on a ledge or flange 42 formed coaxially with the follower member 15^a and received within a bore 12^a with which the inner end of the coupling 75 member 5^a is provided. The outer compression member 35^a is furnished with a series of recesses or pockets 43 adapted to receive the heads of the bolts 32^a.

It will be noted that in this modification 80 of the invention, tightening of the screws 22^a and 32^a will clamp the proximate extremities of the pliant elements E¹ and H¹ between the convex portions 9^a and 28^a of the coupling member 5^a and those of the 85 corresponding and coacting surfaces 18^a and 36^a of the follower members 15^a and 35^a respectively, without any wearing or dragging effect upon the expanded or contracted ends of the tubular lead elements. In order to 90 secure a more positive gripping action in the construction disclosed by the last three figures of the drawing, the curved engaging surfaces of the coacting clamping members may be circumferentially serrated after the 95 manner indicated in Fig. II. When this is done, the serrations of such faces will be caused to bite into the lead sheath and jacket and positively anchor these parts.

In this case, the means 23^a for conducting 100 away electro-static charges occurring at the point of contact of the clamping member 15^a with the insulating envelop C¹, may be made integral with the former instead of being an adjunct to the follower actuating 105 element.

While certain preferred embodiments of this device have been shown and described, it will be understood that changes in the form, arrangements, proportions, sizes and 110 details thereof may be made, without departing from the scope of the invention as defined by the appended claims.

Having described my invention what I desire to secure by Letters Patent and claim, 115 is:—

1. A device for connecting differently sized pliant tubular elements, embodying a coupling member adapted to embrace the smaller element and to be embraced by the 120 larger element, non-rotatable clamping members acting directly against said elements to force them into tight contact with said coupling member, and rotatory means independent of the elements capable of applying pressure upon said clamping members, whereby the said elements are respectively secured to the coupling member 125 without being engaged by relatively rotat- ing parts.

2. A device for connecting differently sized pliant tubular elements, embodying a tubular member adapted to encompass the smaller element near the end of the larger one, a non-rotatable member bearing on the inside of said smaller element to expand it within said tubular member, another non-rotatable member taking over the exterior of said larger element to compress the same into gripping relation with the outside of the tubular member, and means for impelling said non-rotatable members against their respective elements, whereby the latter are clamped to the tubular member without either of them being brought into engagement with relatively rotating parts. 70
3. A device for connecting differently sized pliant tubular elements, embodying a sleeve adapted to embrace one end of the smaller element and to be embraced by the extremity of the larger element, a non-rotatable follower entered into the interior of said smaller element to hold it to the inside of said sleeve, another non-rotatable follower taking over the exterior of said larger element to force the same into gripping relation with the outside of the sleeve, and rotary means independent of both said elements and said followers capable of impelling the latter against the former, whereby the said elements are clamped to the sleeve without being engaged by relatively rotating parts. 80
4. A device for securing a jacket covering a splice between the terminals of electric cables to the conduits thereof, including a sleeve constructed to take over the end of one of the conduits and to enter one extremity of the jacket, an axially movable follower lodged against the inside of said end of the conduit adapted to expand it within said sleeve, another similarly arranged follower embracing said extremity of the jacket capable of forcing the same upon the outside of the sleeve, and rotatable members independent of both of said conduit and said jacket having threaded connection with the sleeve and serving to impel said followers against their respective conduit and jacket, whereby the two latter are clamped to the sleeve without engagement by relatively rotating parts. 90
5. A device for securing a splice enclosing jacket to the conduit terminals of electric cables, including a sleeve member provided interiorly and externally with convex shaped surfaces, and means for forcing the side portions adjacent one extremity each of said jacket and said conduit into tight engagement with said external and interior surfaces respectively. 100
6. A device for securing a splice-jacket to the terminals of cable conduits, including a tubular member formed with an internal substantially bell-shaped surface capable of receiving the end of one of the conduits, said member being provided exteriorly with an approximately bell-like portion adapted to be embraced by one extremity of the jacket, means for expanding said end of the conduit into tight engagement with said internal surface, and other means for contracting said extremity of the jacket to fit closely upon said exterior portion. 105
7. A device for coupling pliant tubular elements of different diameters, including a sleeve member provided internally and exteriorly with belled portions having adjoining abutments, followers formed complementary to said portions and said abutments adapted to bear upon the inside and the outside ends of said elements, and means independent of said followers for forcing them in gripping relation with said ends of the elements against the corresponding parts 85 of said sleeve. 110
8. A device for coupling a larger pliant tubular element to one of smaller diameter, including a sleeve intervening the extremities of said elements and provided on the inside and outside thereof with belled portions having contiguous ledges, the interior ledge adjoining the larger end of the corresponding belled portion, while the external ledge is adjacent the smaller end of the portion thereto appertaining, a follower formed in accordance with the internal configuration of said sleeve adapted to expand the smaller element thereinto, means for impelling said follower against the inside belled portion to tightly grip the extremity of said smaller element therebetween, another follower shaped conformably to the external contour of the sleeve capable of contracting the larger element thereover, and other means for forcing the latter named follower towards the outside belled portion to securely clamp the extremity of said larger element between the last-named parts. 105
9. A device for securing a splice enclosing jacket to the terminals of cable conduits, including a sleeve having opposite portions thereof arranged to take around and enter one extremity each of said conduit and said jacket, said sleeve being provided internally and exteriorly with surfaces adapted to receive the ends of the last named elements, followers formed with complementary surfaces bearing interiorly and externally upon said ends, actuating members connected with the sleeve capable of forcing said followers into gripping relation with the said ends of the conduit and jacket against said first named surfaces, and means extending inwardly of the jacket serving to dissipate 115 electro-static charges occurring between the members of the coupling and the covering of the cable. 120
10. A device for connecting a larger pliant tubular element to one of smaller di- 130

5 ameter, including a coupling member having its opposite ends embraced by and embracing the larger and smaller elements respectively, a follower bearing upon the interior end of said smaller element adapted to expand the same against the inside of said coupling member, an annular member internally engaging the latter capable of actuating said follower, and means for anchoring the extremity of said larger element to the coupling member on the outside thereof.

10 11. A device for connecting a smaller pliant tubular element to one of larger size, including a coupling member formed to receive and to enter the ends of said smaller and larger elements respectively, a follower bearing externally upon the extremity of the last named element capable of contracting

the same over the outside of said coupling member, an annular member exteriorly engaging the latter adapted to actuate said follower, and means for anchoring the terminal of the smaller element within said coupling member.

25

12. A device for connecting differently sized pliant tubular elements, including a coupling member embracing and embraced by the smaller and larger ends of said elements respectively, said member being provided interiorly and externally with oppositely disposed portions, followers complementary to the latter adapted to clamp the extremities of said elements to their respective portions, and an actuating member for 30 35 each of said followers capable of applying pressure thereon.

CLARENCE HERBERT SANDERSON.
